UNITED STATES PATENT OFFICE.

HERMAN E. GABEL, OF LEONIA, NEW JERSEY, ASSIGNOR TO P. R. MITCHELL COMPANY, OF CINCINNATI, OHIO, A CORPORATION OF OHIO.

DESIGN FOR A TEXTILE FABRIC.

Application filed October 7, 1922. Serial No. 3,909. Term of patent 7 years.

To all whom it may concern:

Be it known that I, HERMAN E. GABEL, a citizen of the United States, residing at 153 Sylvan Avenue, Leonia, in the county of Bergen and State of New Jersey, have invented a new, original, and ornamental Design for Textile Fabrics, particularly for cretonnes and ticking in the piece, of which the following is a specification, reference

being had to the accompanying drawing, forming part thereof.

The figure is a plan view of a portion of textile fabric embodying one repeat of the new design.

I claim:

The ornamental design for a textile fabric as shown.

HERMAN E. GABEL.
